CLAIM

The ornamental design for a combined control panel and side panel for a printer, as shown and described.

DESCRIPTION

FIG. 1 is a top, right side perspective view of a combined control panel and side panel for a printer for showing our new design, the broken line showing a printer is for illustrative purposes only and forms no part of the claimed design;

FIG. 2 is a top plan view thereof;

FIG. 3 is a front elevational view thereof;

FIG. 4 is a right side elevational view thereof;

FIG. 5 is a rear elevational view thereof; and,

FIG. 6 is a bottom view thereof.

The left side, bottom and rear of the control panel are not being claimed nor is the front and left side of the side panel.
